2 Claims

ABSTRACT OF THE DISCLOSURE

Clothes drying rack comprising a single elongated rod-like unitary member with a recess defined by a concave portion at one end thereof to receive therein the conventional shower curtain supporting rod. The member defining the rod is of such length as to permit the opposite end thereof to rest against and be supported by the wall parallel with the shower curtain supporting rod. The unitary member defining the drying rack is sufficiently long so that the end thereof, remote from the end engaging the shower curtain supporting rod, will be wedged against the wall at a point slightly above the level of the rod or at a substantially higher lever depending on the spacing between the wall and shower curtain supporting rod. The top edge of the unitary member is provided with serrations or notches to individually receive hangers for clothes to be dried, so the hangers will remain in a predetermined position regardless of the angle at which the unitary elongated member is disposed.

The present invention relates to a clothes drying rack. Specifically, the present invention is concerned with a clothes drying rack comprising an elongated unitary member having one end thereof adapted to be supported by the conventional shower curtain supporting rod and the other end supported by mere engagement with the wall parallel to the shower curtain supporting rod and directly opposite the same.

It has been common practice for many years to use a bathroom and particularly the area over the bathtub or shower stall as a drying area for clothes. Various racks have been employed to support the clothes over such a tub, so that any drip from the clothes will fall into the bathtub or similar area. Heretofore any racks of this nature have been complicated, expensive, and consume a considerable amount of space as far as storage thereof is concerned when not in use.

Since the advent of the so-called drip-dry clothes, there has been even a greater demand for a simple supporting rack for supporting clothes over a bathtub for drying purposes. It would be desirable to provide such a rack in the form of a single unitary elongated member which can be stored in a minimum of space and which can be positioned in a clothes supporting position with a minimum of effort on the part of the user. It would furthermore be desirable to provide such a clothes drying rack which is universally applicable to any bathroom having the conventional shower curtain supporting rod, or similar rod associated with the bathtub or shower stall regardless of the dimensions of the particular installation.

Accordingly, it is an object of the present invention to provide a clothes drying rack in the form of a single, unitary, elongated member which is simple and inexpensive, foolproof in operation, which can be stored in a minimum of space and which may be rendered effective to support clothes over a bathtub in a minimum of time.

It is another object of the present invention to provide an improved clothes drying rack which is supported on one end by the shower curtain supporting rod and on the other end by the wall opposite and parallel with the shower curtain supporting rod and which is adapted to

2

fit in any installation without any adjustment or manipulation with respect thereto.

Still another object of the present invention resides in a single unitary clothes supporting rack adapted to be disposed at various angles with respect to the horizontal and being fully effective at any of these angular positions to support clothes for drying purposes over the conventional bathtub or within the conventional shower stall.

Further objects and advantages of the present invention will become apparent as the following description proceeds, and the features of novelty which characterize the invention will be pointed out with particularity in the claims annexed to and forming a part of this specification.

10 For a better understanding of the present invention reference should be had to the accompanying drawing, in which:

15 FIG. 1 is a fragmentary perspective view of a typical bathroom showing the clothes drying rack of the present invention supporting clothes for drying over the bathtub or other liquid holding unit conventionally found in such installations;

20 FIG. 2 is a fragmentary sectional view taken on line 2—2 of FIG. 1;

25 FIG. 3 is a perspective view of the unitary clothes drying rack of the present invention;

30 FIG. 4 is an enlarged sectional view taken on line 4—4 of FIG. 3; and

FIGS. 5 and 6 are front elevational views, somewhat schematic, showing how the unitary drying rack of the present invention is readily adaptable for use in different situations.

35 Briefly, the present invention is concerned with a unitary elongated rodlike member, preferably molded from a suitable plastic having a recess defined by a concave surface at one end thereof to readily receive therein the conventional shower curtain supporting rod and having along the top edge a plurality of notches, or serrations, to receive clothes hangers in predetermined spaced relationship. The unitary member is of such length as to be longer than the conventional maximum spacing between shower curtain supporting rods and the walls opposite and parallel thereto, so that the end of such member opposite the concave end may be supported by such wall, the particular angle of the member with respect to the horizontal depending upon the spacing between such shower curtain supporting rod and said wall.

40 Referring now to the drawing, there is illustrated in FIG. 1 a portion of a conventional bathroom having either a shower stall or a bathtub, the latter not being shown but being the conventional bathtub or shower stall. As illustrated in FIGS. 1 and 2 of the drawing, the bathroom comprises a recessed area defined by a tiled wall 10 disposed at a right angle to another tiled wall 11. A third wall (not shown) parallel with wall 10 and perpendicular to wall 11 may also be provided to complete the recess for the bathtub or shower stall. The conventional ceiling for the bathtub or shower stall recess is illustrated at 12. Suitably supported by one or more walls, such as 10, is 45 the conventional shower curtain supporting rod 13 which is illustrated as having one end thereof supported, as indicated at 14, by the wall 10. The other end of the rod would be supported in conventional fashion by similar means either to a wall parallel with the wall 10 or by the wall 11 if the rod 13 curves around to support a shower curtain which closes two ends of a bathtub in a well-known manner. The particular construction of the walls 10 and 11 and the supporting means for the rod 13 form no part of the present invention, but are described merely for illustrative purposes.

50 In accordance with the present invention, there is provided an elongated unitary member 15 which may be

formed of any suitable material. Preferably the member 15 is molded from a suitable plastic so as to provide a smooth, rigid, lightweight member which can be molded in a very inexpensive manner. It should be understood that the member 15 might also be formed of metal, wood, or similar rigid material, if desired. In order to provide a rigid member, while still providing a lightweight construction using a minimum amount of material, the unitary member 15 is preferably provided with grooves 16 on either side thereof to define a sort of I-beam, as best shown in FIG. 4 of the drawing.

So that the single unitary member 15 may readily be supported to perform a clothes drying function, one end thereof is provided with a semicircular recess or concave surface 17 of a size and shape as readily to receive therein the conventional shower curtain supporting rod 13 as best shown in FIGS. 1, 5 and 6 of the drawing. The other end of the rodlike member 15 is preferably provided with a curved or rounded surface 18 to readily engage the wall 11 opposite to and parallel with the shower curtain supporting rod 13. The length of the unitary member 15 may vary, if desired, but in a device built in accordance with the present invention, it was found that a length of approximately thirty-one inches measured from the bottom of the recess 17 was satisfactory for almost universal application.

When the spacing between the shower curtain supporting rod 13 and the opposite wall 11 is a maximum, the elongated member 15 of the present invention will assume a position such as shown in FIG. 6 of the drawing with the member 15 almost assuming a horizontal position. On the other hand, when the spacing between the shower curtain supporting rod 13 and the opposite wall 11 is substantially less the elongated unitary member 15 assumes a position represented by FIG. 5 of the drawing at a substantial angle to the horizontal. In either of the extreme positions shown in FIGS. 5 and 6 of the drawing, and in any intermediate positions thereof, the elongated unitary member of the present invention is in an equally good position to support clothes hangers as will become apparent from the ensuing description.

For the purpose of properly spacing clothes and specifically the hangers supporting the clothes on the elongated member 15 of the present invention when positioned as disclosed in FIGS. 1, 5 and 6 of the drawing, the top surface thereof is provided with integral projections 15a of somewhat sawtooth form thereby defining a plurality of notches 20. These notches will assure that the clothes hangers remain in the particular notch in which they are placed, particularly when the angular disposition of the member 15 is such as indicated in FIG. 5 of the drawing. In FIG. 1 there is illustrated by way of example a pair of hangers 21 on each of which is supported a garment designated as 22 and 23, respectively.

In view of the detailed description included above, the operation of the drying rack of the present invention will readily be understood by those skilled in the art. It will be apparent that the single rodlike member 15 comprising the entire clothes drying rack can be stored in any corner. This member 15 can be employed in any bathroom where there is a shower curtain supporting rod parallel to an

opposite wall so that one end of the rack can be applied to the rod and the rack then pivoted about the fulcrum of the rod until it engages the opposite wall, as shown in FIGS. 5 and 6 of the drawing. The spacing between the rod, such as 13, and the opposite wall 11, will determine the angular disposition of the unitary member relative to the horizontal. It will furthermore be apparent that the rack of the present invention can comprise a simple molding which is very inexpensive and can be universally applied by anyone. It will be understood that any suitable resin may be used from which to mold the unitary member 15. One such resin is cellulose acetate butyrate.

While there has been illustrated and described a particular embodiment of the present invention, it will be understood that changes and modifications may occur to those skilled in the art, and it is, therefore, contemplated by the appended claims to cover all such changes and modifications as fall within the true spirit and scope of the present invention.

What is claimed as new and desired to be secured by Letters Patent of the United States is:

1. A clothes drying rack comprising an elongated substantially straight unitary member having a concave recess defined in one end, said member having a length greater than the maximum spacing between the conventional shower curtain supporting rod and the wall opposite to said rod and parallel with the longitudinal axis of said member when said other end engages said wall, other end for engaging said wall whereby said member is supported by said rod on one end and said wall at the other end, and notches along the top edge of said member to hold means for supporting clothes to be dried in spaced relationship regardless of the angular disposition of said member when said other end engages said wall, said notches being shaped to prevent said means for supporting clothes to be dried from moving toward the end of said unitary member having said concave recess therein.

2. The clothes drying rack of claim 1 wherein said member is molded from a resin.
